UNITED STATES PATENT OFFICE

2,029,927

WATER HEATER

Thomas H. Ireland, Rockville Centre, N. Y.

Application September 28, 1934, Serial No. 745,841

6 Claims. (Cl. 257—254)

The invention relates to water heaters and particularly to utilizing a conventional range boiler as a unit part of the heater or, in other words, associating the water heater and heating medium employed with a boiler of the class described, and the object of the invention is to provide a water heating unit employing a range boiler with a heating coil associated with and arranged beneath the boiler, with a source of heat supply disposed immediately below the heating coil, whereby the products of combustion radiating from the heating medium may be directed first onto the coil and then upon the boiler; a further object being to provide a water heating member or coil comprising a series of tubes open at one end, each tube containing a baffle or partition plate forming circulating passages within the tubes and detachable plugs at the open ends of the tubes, facilitating the removal of the plates and the cleaning of the tubes and plates whenever desired; and with these and other objects in view, the invention consists in a heater unit of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side and sectional view of the unit made according to my invention with part of the construction broken away.

Fig. 2 is a partial section on the line 2—2 of Fig. 1.

Fig. 3 is a partial section on the line 3—3 of Fig. 2.

Fig. 4 is a detail plan and sectional view of a modified form of heater which I may employ, and,

Fig. 5 is a perspective view of one of the baffle plates which I employ.

In Fig. 1 of the drawing, I have indicated at 10 a range boiler or hot water tank of more or less conventional form supported on a stand 11 provided at its upper end with a flanged ring 12 upon which the boiler or tank seats. The water supply and discharge tubes to the tank or boiler are not shown but these will be of the conventional or any desired arrangement. But, at 13 I have shown the usual drain pipe extending from the bottom wall of the boiler, which pipe is provided with a usual valve or shut-off, not shown.

At 14, I have shown the cold water circulating pipe extending from the lower portion of the boiler 10, and connected, as indicated at 15, with my improved water heater 16, a union 14a being incorporated in the pipe 14 to facilitate the mounting of the water heater as will be apparent.

The water is discharged from the heater 16 through a pipe 17 which couples with a fourway coupling 18 with which the hot water supply pipe 19 is also coupled, the latter extending to and being connected with the upper end of the boiler as indicated at 20. Clean out plugs 18a are provided on the coupling 18 to facilitate cleaning out the pipes 17 and 19.

In the construction shown I employ a skirt or jacket portion 21 which extends downwardly from the ring 12 and envelops the stand 11, water heater 16, as well as the gas burner 22, or other heating medium or source of heat supply. In other words, the skirt or jacket 21 forms what 20 might be termed a heater casing which is positioned directly below the boiler 10. The burner 22 is supported on transverse straps 23 and the rear end of the water heater 16 is supported on a transverse strap or rod 24, the forward end 25 being supported by the pipes 14 and 19 and the connections thereof. At the lower portion of the skirt 21 are a number of air inlet openings 25 for supply to the burner 22. At one side of the boiler is an elbow exhaust 26 for the discharge of products of combustion from the chamber 21a within the skirt 21.

The water heater 16 as shown in Figs. 1 to 3 inclusive consists of a casing 27 having one longitudinal passage 28 extending therethrough, and three transverse passages 29, 30, and 31, the forward ends of which are closed by plugs 29a, 30a, and 31a, and coupled with the rear ends thereof are elongated thimble shaped tubes 32, 33, and 34. In each of these tubes are arranged baffle or partition walls 35, 36, and 37, the forward end portions of which are provided with laterally extending ears 38 which set in slots 39 formed in the casing 27 at the inner end of the plugs 29a, 30a, and 31a so as to position the baffle plates 35, 36, and 37 in the diagonal arrangement illustrated clearly in Fig. 3 of the drawing to provide at the lower side of the circulating tubes 32, 33, and 34, passages 40 and at the upper portions 50 thereof, passages 41 placed in connection at the rear closed ends of the tubes 32, 33, and 34 as indicated at 42, the latter being formed by projecting stop pins or fingers 43 at the inner ends of the plates 35, 36, and 37. In Fig. 5 of the drawing 55

I have shown a detail view of the baffle plate 35 on an enlarged scale clearly illustrating the ears 38 and the finger 43.

In other words, in the construction shown in Figs. 1 to 3 inclusive the heater 16 is made up into three tubes, each subdivided by a baffle or partition plate to divide the same into what may be termed intake passages 40 and exhaust passages 41 placed in communication at the inner ends of the tube as at 42 so that cold water entering through the pipe 15 will first pass into the bore 28 below the plate 35, flow backwardly through the passage 40 and then forwardly through the passage 41 in the tube 32, again into the bore 28 beneath the plate 36, pass successively through the tubes 33 and 34 in the same manner, and finally discharge through the pipe 17 from which it will pass into the pipe 19 and thus into the boiler 10. In other words, the circulation becomes continuous when the burner 22 is in operation to circulate water from the bottom of the boiler back and forth through the tubes of the heater 16 and to the tube of the boiler. From time to time, and especially in using heater units of this type with certain types of water supplies, a formation of scale or sediment is experienced in the pipes, tubes, and the like of the heater unit and the circulating pipes of the system. For this reason, the plugs 29a, 30a, and 31a are employed to facilitate removal of the plates 35, 36, and 37 to clean off said plates as well as the tubes 32, 33, and 34. The plugs 18a may also be removed to clean out the longitudinal passage or bore 28, the pipe 17 and the pipe 19, thus keeping the circulating system absolutely clean at all times and in like manner maintaining the most efficient heating exchange between the burner 22 or other heating mediums employed and the walls of the tubes of the burner.

40 It will be understood that instead of arranging the member 16 in a straight horizontal plane as indicated in Fig. 1 the same may be disposed in an inclined plane with the end attached to the pipe 17 higher than the end attached at the pipe 15 to increase circulation.

45 In Fig. 4 of the drawing I have shown a slight modification of the structure shown in Figs. 1 to 3 inclusive wherein the water heater 16a has its tubes 32a, 33a, and 34a, cast or otherwise formed integral with the casing 21a and aside from this structural change the heater 16a is the same as the heater 16 and operates in the same manner.

50 It will also be seen upon consideration of Fig. 2 of the drawing that a cover 44 may be formed on the casing or skirt 21 in alinement with the plugs 29a, 30a, and 31a to give access thereto whenever desired, the cover being hinged as is indicated at 45.

55 By constructing a water heating unit in conjunction with a boiler or other storage tank in the manner described a very simple as well as efficient type of unit is provided, it being understood that the products of combustion rising above the heater 16—16a and circulating around the tubes thereof are directed upon the bottom of the boiler and serve to partially heat the water in the bottom of the boiler and to this degree render the heater unit more efficient.

60 It will be understood that my invention is not necessarily limited to the specific arrangement of parts herein shown and described nor to the number of circulating tubes employed in the heater, and still further, it will be apparent that the device may be utilized as a heat exchanger.

65 It will also be apparent that my invention may

be applicable for use as a household heater or built on a larger scale to satisfy greater volume of supply and still further may be used for commercial purposes. But, in all cases the fundamental plan of the unit will be carried out.

Having fully described my invention, what I claim as new and desire to secure by Letters Patent, is:

1. A heat exchanger device comprising a casing having a continuous bore extending longitudinally therethrough, a plurality of tubes radiating from said bore at spaced intervals longitudinally thereof, the chambers of said tubes opening into and being in communication through said bore, means arranged longitudinally of said tubes and extending through said bore for subdividing the tubes into independent circulating passages placed in communication with each other at the free end of the tubes said last named means comprising plates, and the casing having spaced passages in alinement with said tubes and communicating with the bore of said casing to provide attachment and detachment of the plates with respect to said tubes.

2. A heat exchanger device comprising a casing having a continuous bore extending longitudinally therethrough, a plurality of tubes radiating from said bore at spaced intervals longitudinally thereof, the chambers of said tubes opening into and being in communication through said bore, means arranged longitudinally of said tubes and extending through said bore for subdividing the tubes into independent circulating passages placed in communication with each other at the free end of the tubes, said last named means comprising plates, the casing having spaced passages in alinement with said tubes and communicating with the bore of said casing to provide attachment and detachment of the plates with respect to said tubes, plugs detachable from the casing for closing each of said passages, and means on the plates and in said casing for keying the plates against rotation in the casing and said tubes.

3. A heat exchanger device comprising a casing having a continuous bore extending longitudinally therethrough, a plurality of tubes radiating from said bore at spaced intervals longitudinally thereof, the chambers of said tubes opening into and being in communication through said bore, means arranged longitudinally of said tubes and extending through said bore for subdividing the tubes into independent circulating passages placed in communication with each other at the free end of the tubes, said last named means comprising plates, the casing having spaced passages in alinement with said tubes and communicating with the bore of said casing to provide attachment and detachment of the plates with respect to said tubes, plugs detachable from the casing for closing each of said passages, and means on the plates and in said casing for keying the plates against rotation in the casing and said tubes, the said plates being arranged in each tube in an upwardly inclined direction with respect to the longitudinal plane of the bore in said casing.

4. A fluid heater of the class described comprising a plurality of laterally spaced tubes, one end of said tubes being closed, the other end thereof being open, means for placing the open ends of said tubes in communication with each other, a plate arranged in each tube and extending into said last named means to divide each tube and the communicating means into independent passages to form through the series

of tubes, a continuous coil-like passage extending forwardly and backwardly through the respective tubes in successive order, and means on said plates and in said first named means for retaining said plates in predetermined position in the respective tubes.

5. A fluid heater of the class described comprising an elongated casing having a continuous bore extending longitudinally therethrough and opening through opposite ends thereof, a plurality of openings spaced longitudinally in one side wall of the casing and extending into said bore, a plurality of tubular members opening into the bore and extending from the opposite side of the 10 casing in alinement with said openings, a plate mounted in each tube through the opening arranged in alinement therewith, said plate being keyed to said casing and transversing the bore thereof to divide said bore and the tube into independent side passages placed in communication 15 at the free ends of the tubes, and plugs for closing the openings of said casing.

6. A fluid heater of the class described comprising an elongated casing having a continuous bore extending longitudinally therethrough and opening through opposite ends thereof, a plurality of openings spaced longitudinally in one side 5 wall of the casing and extending into said bore, a plurality of tubular members opening into the bore and extending from the opposite side of the casing in alinement with said openings, a plate mounted in each tube through the opening arranged in alinement therewith, said plate being keyed to said casing and transversing the bore thereof to divide said bore and the tube into independent side passages placed in communication 10 at the free ends of the tubes, and plugs for closing the openings of said casing, the said plate comprising a thin metal strip provided with laterally extending key lugs at one end and a projecting finger centrally of the other end thereof. 15 20
